The ornamental design for a utility basket attachment for a traveling bin, as shown and described.

DESCRIPTION

FIG. 1 is a top perspective view of a utility basket attachment for a traveling bin showing our new design;

FIG. 2 is a bottom perspective view thereof;

FIG. 3 is a front elevational view thereof;

FIG. 4 is a left elevational view thereof;

FIG. 5 is a right elevational view thereof;

FIG. 6 is a back elevational view thereof;

FIG. 7 is a bottom plan view thereof;

FIG. 8 is a top plan view thereof;

FIG. 9 is a top perspective view thereof, shown in a state of use; and,

FIG. 10 is another top perspective view thereof, shown in state of use.

The broken lines showing portions of a traveling bin and tools depict environmental subject matter that forms no part of the claimed design.
